UNITED STATES PATENT OFFICE.

JOHN STEVENS, OF NEENAH, WISCONSIN.

DAMPENING-BRUSH.

SPECIFICATION forming part of Letters Patent No. 307,877, dated November 11, 1884.

Application filed May 1, 1883. (No model.)

To all whom it may concern:

Be it known that I, JOHN STEVENS, of Neenah, in the county of Winnebago and State of Wisconsin, have invented certain new and 5 useful Improvements in Damping-Brushes for Letter-Books, of which the following is a specification.

My invention has for its object to so construct a damping-brush that it may carry a 10 reservoir of water from which supplies may be drawn directly upon the brush to keep it moist; and it consists in combining with the reservoir-handle and a transverse perforated tube supplied therefrom and discharging along 15 the head of the brush a removable brush that may be renewed when worn; in combining with the reservoir and transverse perforated tube supplied therefrom a brush beneath said tube, and a cap to inclose the brush and keep 20 it moist, and in the various other combinations and details of construction hereinafter pointed out and claimed.

In the drawings, Figure 1 is a vertical central section, partly in elevation, through a damping-brush constructed in accordance with my 25 invention; Fig. 2, a transverse section thereof on the correspondingly-numbered line in Fig. 1; Fig. 3, an elevation, partly broken away, of an alternative construction; and Fig. 4, a 30 transverse section of the foregoing.

The invention may be applied in connection with a camel's-hair brush, and in the first two figures I have shown it so; but it has also enabled me to use a sponge instead of a hair 35 brush, and I have found this so desirable and beneficial in its effects, easily kept at just the proper degree of dampness, and moistening the paper evenly, that I am inclined to prefer it, and have therefore shown it in the last two 40 figures.

A is the reservoir, narrowed at one end into the handle A', which is advisably connected with the body portion by a screw-joint, so that it may be removed to give access to the interior, and which forms a continuation of the 45 reservoir. At the end of this handle is an aperture with a screw-cap, a, through which the brush may be filled; but this aperture and cap may be at any other convenient place. At 50 the bottom the reservoir is flattened and elongated to about the usual width of damping-brushes to receive the brush proper. A tube,

a', leads from the reservoir downward into this flattened or elongated portion, and enters a cross-tube, a'', which is either beneath the floor 55 of the reservoir, extending from end to end of the flattened portion, or itself by its imperforate upper half forms a floor. Along the bottom of this transverse tube it is perforated at regular distances to discharge the water it 60 receives upon the head of the brush beneath. The first or upright tube has a lateral aperture or opening, b, within the reservoir, just above the bottom, which is closed by a valve on one arm of a valve-lever, B, pivoted in 65 ears b' from the upper end of the tube, or from a bracket or any suitable bridge within the reservoir. A rod, b'', is pin-jointed to the power-arm of the valve-lever, and passes through a guide-eye in a bridge, b', into a lateral recess 70 or extension from the side of the reservoir. At its end it is headed or has a button, and between this button and the bridge is a coiled spring, b', which tends by its force to hold the valve-lever constantly shut, preventing the 75 escape of water from the reservoir. This lateral recess or chamber is closed by a flexible diaphragm, C, advisably made in the form of a screw-cap, that it may be applied and adjusted to the proper position for its work. 80 When the valve is closed and the diaphragm distended in its normal position, its inner surface is close to the button on the end of the valve-rod, but not exactly in contact therewith. If, however, it is desired to supply wa- 85 ter to the brush, the diaphragm will be depressed by the finger or thumb, forcing in the valve-rod and opening the valve, and at the same time slightly compressing the air within the reservoir to cause a better flow. When 90 released, it will return elastically to its distended state, and the spring-pressed valve-rod will at once close the valve and stop the flow of water.

In using the camel's-hair brush D the base 95 of the brush will be confined in a metal head or socket, D', of wedge shape, as shown, and a truncated sleeve open at both ends will be constructed of such size and shape as to receive this socket and allow the brush to project from its own lower and smaller mouth, while the larger is slipped over and embraces the base of the reservoir. Space will be left 100 between the walls of the socket and of the

sleeve for water to pass through and come in contact with the brush. By removing the sleeve the brush can be withdrawn and changed, supposing it to be worn.

5 As already stated, I prefer a sponge, C', to camel's hair. With this the metal head or crown is dispensed with, and the lower lips of the sleeve are turned in or serrated, as in Fig. 3. The sponge is cut in a long strip, and 10 the sleeve being removed from the reservoir, it is inserted through the upper or larger mouth and crammed down until a sufficient portion projects beyond the lower lips and is held by their inward bend, or by the serrations. Should the sponge be uneven after 15 having been thus applied, it may be trimmed by shears or scissors; and when it is worn or rotten it can be torn out and a new strip inserted. To keep it from drying rapidly when 20 the brush is not in use, a cap, D², is formed to inclose it and slip upon the sleeve.

The general shape of the fountain-brush as thus described is not materially different from the shape of other dampening-brushes heretofore in use. It will, however, carry a day's 25 supply of water, or nearly that, in its reservoir, and the moisture supplied to it will be under better control than where it has to be dipped constantly into a dish.

30 In Letters Patent No. 288,598, granted to me on the 13th day of November, 1883, I have described and made the subject of the first claim therein the combination, with a reservoir and brush and laterally-apertured connecting- 35 tube, of a valve, valve-rod, and spring to close the aperture, and a diaphragm above the end of the valve-rod, whereby said rod may be depressed to move the valve and open the aperture; hence I do not herein intend to cover

such combination, broadly, or apart from other 40 elements and features peculiar to the present invention; but

I claim as my invention—

1. The combination, substantially as hereinbefore set forth, in a fountain-brush, of the 45 reservoir, narrowed and elongated at its lower end, the perforated tube or pipe running from end to end of said elongated portion beneath the reservoir, the sleeve slipped on and off of said elongated portion, and the removable 50 brush carried in such sleeve.

2. The combination, substantially as hereinbefore set forth, in a fountain dampening-brush, of the reservoir, its eduction-tube, the 55 valve-lever closing the eduction-opening, the transverse tube to which the eduction-tube delivers, perforated along its bottom, the sleeve, and the sponge held by said sleeve beneath the transverse tube.

3. The combination, substantially as hereinbefore set forth, in a fountain dampening-brush, of the reservoir, its eduction-tube, the 60 transverse tube to which said eduction-tube delivers, the ears on the eduction-tube, the valve-lever pivoted therein, the valve-rod and 65 its spring, and the diaphragm.

4. The combination, substantially as hereinbefore set forth, in a fountain dampening-brush, of the reservoir, its eduction-tube, the 70 perforated transverse tube to which said eduction-tube delivers, the brush beneath the transverse tube and moistened therefrom, and the cap to cover said brush and retain the moisture.

JOHN STEVENS.
